UNITED STATES PATENT OFFICE.

ISAAC N. HANNOLD AND JOHN W. SINNICKSON, OF PHILADELPHIA,
PENNSYLVANIA.

DESIGN FOR A TARGET.

SPECIFICATION forming part of Design No. 26,600, dated February 2, 1897.

Application filed September 16, 1896. Serial No. 606,056. Term of patent 14 years.

To all whom it may concern:

Be it known that we, ISAAC N. HANNOLD and JOHN W. SINNICKSON, citizens of the United States, and residents of Philadelphia, Pennsylvania, have invented a certain new and original Design for a Target, of which the following is a specification.

Our design for a target is fully shown in the accompanying drawings, in which—

Figure 1 represents a face view of the target; and Fig. 2 is a sectional view of the same on the line 2 2, Fig. 1.

The target comprises a central disk *a* and a series of concentric rings *b*, the first of these rings being separated from the central disk and the successive rings being separated from

each other, so as to provide intervening spaces *c*. The central disk and each of the concentric rings have rounded or inturned edges, as shown in Fig. 2. 20

We claim—

The design for a target, substantially as described and as shown in the accompanying drawings.

In testimony whereof we have signed our names to this specification in the presence of two subscribing witnesses.

ISAAC N. HANNOLD.
JOHN W. SINNICKSON.

Witnesses:

MURRAY C. BOYER,
WILL A. BARR.
